[57] CLAIM

The ornamental design for an air conditioner, as shown and described.

DESCRIPTION

FIG. 1 is a perspective view of the inventive air conditioner;

FIG. 2 is a front view of the air conditioner;

FIG. 3 is a top plan view of the air conditioner;

FIG. 4 is a rear view of the air conditioner;

FIG. 5 is a bottom view of the air conditioner;

FIG. 6 is a right side view of the air conditioner, the opposite side being a mirror image of that shown;

FIG. 7 is a sectional view taken along line 7—7 in FIG. 2;

FIG. 8 is a sectional view taken along line 8—8 in FIG. 2; and,

FIG. 9 shows the air conditioner on a reduced scale in use.

The broken line showing of environmental structure in FIG. 9 is for illustrative purposes only and forms no part of the claimed design.
